UNITED STATES PATENT OFFICE.

GILLES HOLST, OF EINDHOVEN, NETHERLANDS, ASSIGNOR TO N. V. PHILIPS' GLOEILAMPENFABRIEKEN, OF EINDHOVEN, NETHERLANDS.

ELECTRODE FOR DISCHARGE TUBES.

Application filed May 11, 1926, Serial No. 108,346, and in the Netherlands June 8, 1925.

This invention is concerned with improved electrodes for discharge tubes consisting of a continuous conductor bent helically or in a zigzag line.

5 Frequently drawbacks have been experienced when using this kind of electrodes, their deprivation of occluded gases being beset with difficulties. In order to obviate the said disadvantage it has already been suggested to connect the two ends of a helical electrode to leading-in wires and to lead a current through the electrode while the discharge tube is being deprived of occluded gases. However, when using these electrodes

10 there is the risk that during their calcination which has to be effected at a very high temperature they sag, which prevents the correct mutual distance of the electrodes in the discharge tube from being maintained.

15 20 It has also been already suggested to secure the turns of the helical electrode to a rod of insulating material. This presents however the disadvantage that while the helical conductor is being heated the insulating material cannot be heated to a satisfactory extent so that it cannot be deprived of occluded gases and consequently evolves contaminating substances during the use of the electrode in the discharge tube.

25 30 Moreover, the application of the insulating material in the direct proximity of the electrodes causes static discharges which likewise entails difficulty during the use. The invention obviates the said disadvantages,

35 40 the small supporting rod of the conductor bent helically or in a zigzag line consisting of material having a substantially higher specific resistance than the material of the bent conductor. This enables a current to be led during the deprivation of the discharge tube of gases both through the bent conductor constituting the electrode proper and through the small supporting rod so as to deprive the two elements simultaneously of occluded gases.

45 50 By imparting to the bent conductor a materially lower specific resistance than to the supporting rod it is ensured that a large part of the current supplied is led through the said conductor.

55 60 Moreover a poor heat conduction is nearly always incidental to a high specific resistance so that the Joule-heat stored in the supporting rod during the deprivation of

gases is conducted away to the poles only to a low extent but is led essentially to the 55 turns or undulations of the electrode proper, which latter is not only possessed of a greater electric conduction but also of a higher conductivity for heat. Materials which have been proved highly adapted for 60 the object of the invention are constantin and nickel, the former as a material for the supporting rod, the latter as a material for the electrode proper.

The invention will be more clearly understood by reference to the accompanying drawing. In the said drawing a three-electrode tube having a helical grid electrode is shown by way of example. In the said drawing 1 is a stem tube which ends in a 70 pinch 2 in which the various supports and leading-in wires are sealed. The supporting wires 3 and 4 serve to support the anode 5 which has a cylindrical shape in the construction illustrated. The support 4 is connected to a leading-in wire 6. Further supporting wires 7 and 8 are arranged to support a helical grid electrode 11. The supporting wires 7 and 8 are connected to leading-in wires 9 and 10 respectively, which 75 renders it possible to heat the grid galvanically during the deprivation of gases. The helical conductor 11 preferably consists of nickel or any other material being a good conductor of electricity and being also 80 readily deprived of occluded gases. The successive turns of the helical conductor 11 are secured to a small supporting rod 12 of constantin or other metal which is a poor conductor of heat and has a high specific 85 resistance. The attachment of the turns to the supporting rod is preferably effected by welding. An incandescent cathode 13 in the form of a stretched wire is secured to two supporting wires 14 and 15, which latter are 90 connected to leading-in wires 16 and 17.

95 It is obvious that the invention can be applied not only to three-electrode tubes but also to discharge tubes having more than three electrodes, in which the controlling 100 grid as well as the auxiliary grid or grids may be manufactured in accordance with the invention. The invention can also be applied to electrodes which are not helical as in the construction illustrated but consist 105 of a conductor in a zigzag line located in a

plane. Moreover the invention can be applied to anodes consisting of a continuous bent conductor.

What I claim is:—

5. 1. In a discharge tube, electrode supports, a lead-in wire connected to each support, an electrode of such a form that it is longer than the distance between its supports, and a rod for supporting said electrode to prevent its sagging when heated, said rod being an electrical conductor and having electrical connection with the electrode lead in wires.
10. 2. In a discharge tube, electrode supports, a lead-in wire connected to each support, an electrode of such a form that it is longer than the distance between its supports, and a rod for supporting said electrode to prevent its sagging when heated, said rod being an electrical conductor and having electrical connection with the electrode lead in wires, said electrode having an electrical resistance greater than the resistance of the electrode.
15. 3. In a discharge tube, electrode supports, a lead-in wire connected to each support, an electrode of such a form that it is longer than the distance between its supports, and a rod for supporting said electrode to prevent its sagging when heated, the rod being
4. attached to the electrode supports, said rod being an electrical conductor having a specific resistance greater than the specific resistance of the electrode.
5. 4. In a discharge tube, a pair of electrode supports, each support having a lead-in connection, a nickel electrode of such form that it is longer than the distance between its supports, and a rod for supporting said electrode to prevent its sagging when heated, said rod being an electrical conductor having a specific resistance of about 50 microhms per cubic centimeter.
45. 5. In a discharge tube, a pair of electrode supports, each support having a lead-in connection, a nickel electrode of such form that it is longer than the distance between its supports, and a rod positioned beneath the electrode such that portions of the electrode rest upon the rod and are supported thereby to prevent sagging of the electrode when heated, said rod being an electrical conductor having a specific resistance of about 50 microhms per cubic centimeter.

In testimony whereof I affix my signature, at the city of Eindhoven, this 23rd day of April, A. D. 1926.

GILLES HOLST.
